UNITED STATES PATENT OFFICE

2,488,617

SLEEVE STRETCHER

Lynn W. Butcher, Chinook, Mont.

Application December 2, 1947, Serial No. 789,145

1 Claim. (Cl. 223—72)

1

This invention relates to a sleeve stretching means for use in smoothing out a sleeve during the ironing thereof.

An object of this invention is to provide a sleeve stretcher which is insertable in a sleeve for smoothly stretching the sleeve so as to permit the ironing of the sleeve and elimination of wrinkles.

Another object of this invention is to provide a device of this kind which includes a pair of divergent spring members connected at their outer convergent ends to a U-shaped handle which is also formed of resilient material so that when the device is inserted within a sleeve the device will spring outwardly and smoothly stretch the sleeve so that the latter may be ironed between the resilient arms and wrinkles eliminated.

Another object of this invention is to provide a device of this kind which is of simple construction and formed out of resilient material such as spring wire or the like, which will occupy only a very small space within the sleeve thereby permitting the ironing of the sleeve between the resilient arms.

With the above and other objects in view, my invention consists in the arrangement, combination and details of construction disclosed in the drawings and specification, and then more particularly pointed out in the appended claim.

In the drawings.

Figure 1 is a detailed side elevation of a device constructed according to an embodiment of this invention, mounted in a sleeve,

Figure 2 is a detailed side elevation partly broken away of the device, and

Figure 3 is an edge view of the device.

Referring to the drawings, the numerals 10 and 11 designate a pair of divergent, resilient arms which are formed of wire and are provided at their inner ends with reverted bends 12 and 13.

The outer end portions of the arms 10 and 11 include obtusely bent intermediate portions 14 and 15 respectively, which are adapted to engage that portion of a sleeve S adjacent the cuff C. The obtuse extensions 14 and 15 merge with parallel extensions 16 and 17 respectively, which are adapted to engage within the cuff C and the parallel extensions 16 and 17 merge with obtusely bent extensions 18 and 19 respectively.

The obtuse extensions 18 and 19 are secured to or formed integral with a U-shaped handle 20 which, as shown in Figure 3, is formed of flat spring material.

2

The wire from which the arms 10 and 11 with the extensions 14, 15, 16, 17, 18 and 19 are formed, is constructed out of resilient material such as spring wire or the like which is properly tempered so that the wire will retain its normal shape during the insertion of the device within the sleeve and the straight arms 10 and 11 will be maintained substantially straight when in inserted position.

10 In the use of this device, the handle 20 is compressed so as to swing the arms 10 and 11 toward each other and these arms are then inserted through the cuff C into the sleeve S. When the cuff C engages over the cuff stretching or smoothing arms 16 and 17, the handle 20 may be released so that the spring arms 10 and 11 may spring away from each other so as to thereby stretch the sleeve S therebetween.

The sleeve may then be ironed between the arms, and if it is desired to form tight creases after the main body of the sleeve has been ironed, the stretcher or smoothing member may be removed and the edges of the sleeve ironed without the device therein.

25 Having thus described my invention, what I claim is:

A sleeve stretcher for use in ironing a shirt sleeve, comprising a pair of elongated wire spring arms disposed in inwardly divergent relation, 30 outwardly converging obtuse extensions extending from the forward or outer ends of said arms, parallel extensions extending from the forward ends of said obtuse extensions, said outwardly converging obtuse extensions extending from the 35 outer ends of said parallel extensions and a U-shaped resilient handle formed integral with and extending from the outer ends of said latter named obtuse extensions, said divergent arms being engageable within the body of a sleeve for 40 stretching the sleeve therebetween and said parallel extensions being engageable within the cuff to thereby smooth the cuff.

LYNN W. BUTCHER.
